UNITED STATES PATENT OFFICE.

ERNEST F. LLOYD, OF DETROIT, MICHIGAN.

PRESSURE-INCREASER.

1,090,866.

Specification of Letters Patent. Patented Mar. 24, 1914.

Application filed December 21, 1911. Serial No. 667,097.

To all whom it may concern:

Be it known that I, ERNEST F. LLOYD, a citizen of the United States of America, residing at Detroit, in the county of Wayne and State of Michigan, have invented certain new and useful Improvements in Pressure-Increasers, of which the following is a specification; reference being had thereto to the accompanying drawings.

10 This invention relates to gas distributing systems and more especially to a pressure increaser or means in the system for automatically controlling the flow of gas or the like through a main or conduit whereby the 15 pressure at a given point in the main is made to build up as the volume of gas passing such point increases.

The invention consists in the matters hereinafter set forth and more particularly 20 pointed out in the appended claims.

In the drawings, Figure 1, is a view partially in section and partially in elevation, of an apparatus embodying features of the invention; Fig. 2, is a plan view in detail 25 of a loader connection for a master valve; and Fig. 3 is a view in section and in detail of a master valve.

As shown in the drawings, a main or conduit has an automatic regulating valve 30 1 that controls the flow from the inlet arm 2 of the main to the outlet arm 3 and holds the pressure in the latter arm under ordinary conditions at a constant point in relation to atmospheric pressure. The pressure in 35 the inlet arm 2 is higher than that in the outlet 3.

In preferred form the valve 1 has a pair 40 of closures 4 adapted to close on annular seats 6 in the valve casing. The stem 7 carrying the closures operatively connects them to a movable or flexible diaphragm 8 that divides a drum 9 into an upper and a lower compartment. A tension spring 10 in a tubular extension 11 of the drum may be 45 adjusted on a suspending screwthreaded rod 12 to exert a constant upward pull on the diaphragm 8.

A pipe 13 connects the lower compartment 50 of the drum 9 with one outlet of a master valve 14 and the other drum chamber is in communication through a pipe 15 with another outlet of the same valve. A pressure or power gas pipe 17 connects the inlet of the master valve with the high pressure or inlet arm 2 of the conduit, or other 55 source of supply of gas under pressure. A

waste pipe 19 leads from an exhaust opening in the valve to the low pressure arm 3 of the conduit. While the master valve may be of any desired construction it preferably is made with a stem 18 on which are a pair of closures 20 and 21 in spaced relation, the upper closure 20 playing between a pair of valve seats 22 and 23 on opposite sides of an outlet 24 with which the pipe 60 13 is connected, and the lower closure 21 moving between seats 25 and 26 disposed on opposite sides of an outlet 27 into the pipe 15. The inlet 28 of the pressure or power gas pipe 17 is between the two pairs of seats 70 while the exhaust opening 29 of the valve into the waste pipe 19 is connected with a by-pass 30 in communication with the spaces between the valve seats as shown. The stem 18 may extend through a stuffing 75 box, or, preferably, a packing diaphragm 31 into a drum 32 and is connected to a movable or flexible diaphragm in the latter, whereby the pressure of gas introduced beneath the diaphragm through a pipe 34 80 from the outlet arm of the conduit acts to raise the stem against weights 35 placed on a receptacle or bowl 36 of the stem. Thus as the pressure increases in the outlet arm of the main causing the stem 18 to rise, the 85 tendency of the master valve is to shunt gas from the pressure or power gas pipe 17 through the pipe 13 under the lower side of the diaphragm 8 of the regulating valve 1 and thereby close the latter correspondingly, the gas in the upper compartment of the drum 9 escaping through the pipe 13 and the waste pipe 19 into the low pressure arm of the conduit or elsewhere. Conversely when the pressure in the outlet arm of the 90 conduit falls the weights of the stem 18 lower the latter so that the master valve tends to deliver the power gas through the pipe 15 on to the diaphragm 8 and open the regulating valve correspondingly, the gas 100 in the lower compartment of the drum escaping through the pipe 13 and waste pipe 19.

The weights on the closure stem of the master valve determine the range of action of the governor which tends to hold the pressure substantially constant in the outlet arm. Such pressure may be termed "normal" or "set." In order, however, that the regulator may allow the pressure to increase as the volume of gas passing through the 105 outlet increases, means operated by an artificial or local drop in pressure at a given 110

point preferably in the outlet arm are employed to increase the weight on the master valve, and thus cause the latter to open the regulating valve when under "excess pressure" or pressure above the "normal." Preferably, this weight increasing means is of the type described in my application filed February 14, 1911, Serial No. 608,487, for mercury loaders. A valve 37 forms a convenient and adjustable adjutage for causing the desired drop. A by-pass 38 is placed around this point of drop and a Venturi tube 39 is inserted in the by-pass for multiplying the effect of the differential or velocity pressure thus obtained. The pipe 40 from the head of the venturi enters the compartment of a pressure drum 41 of a loader above a movable or flexible diaphragm 42. A throat pipe 43 from the venturi communicates with the drum below the diaphragm. A stem 44 moved by the diaphragm 42 passes up through the well 45 of a float chamber 46, with a tubular sleeve 47 depending over the well and carrying a displacement float 48. The chamber, which is disposed at an appropriate level in relation to the bowl 36 of the master valve and is filled with mercury or like weighting fluid to the desired depth, has a transverse pipe 49 that leads to the bowl 36 through a flexible hose 51 or the like entering the latter and permitting free movement of the same. As a matter of convenience a casing 50 shields the bowl and forms a support for the transfer pipe. As the velocity pressure of the venturi increases the resultant downward movement of the diaphragm 42 depresses the float 48 thereby forcing the level of the mercury in the chamber up into the narrow annular space between the float and chamber wall, so that it flows over into the bowl thereby increasing the load on the latter and tending to shunt the power gas to open the regulating valve 1. A stop screw 52 or the like limits the downward movement of the diaphragm 42 and displacement float 48 so that the apparatus may be set to impose only a predetermined maximum of excess load on the master valve. This form of displacement loader for the master valve is preferable although obviously other types may be used which transfer weight or the pull of weights to add to the load of the master valve.

In operation, the regulating valve is controlled by the master valve to hold a desired pressure in the outlet arm of the main within a range determined by the weights placed upon the master stem valve, such weights being adjustable to meet conditions of service. Beyond this range the loader acts to cause a rise and fall of pressure above the "normal" or "set" pressure in exact proportion to variations in volumes of flow. The volume of flow to cause a de-

sired drop may be varied by changing the adjustment of the adjutage valve. In other words, the apparatus has two independent adjustments, one for obtaining the "normal" outlet pressure desired, the other for obtaining a surplus volume of flow and for limiting the maximum "excess" pressure to be obtained.

Obviously, changes in the details of construction may be made without departing from the spirit of the invention and I do not care to limit myself to any particular form or arrangement of parts.

I claim:

1. The combination with a conduit, of regulating means controlled by fluid pressure for automatically maintaining a constant pressure in the outlet side of the conduit, means for controlling the admission of fluid under pressure to operate the regulator, means for setting up a drop in pressure in the conduit, and means controlled by variations in the drop in pressure and adapted to control the pressure fluid admitting means by gravity to raise the pressure in the conduit as the flow past the point of drop increases.

2. The combination with a conduit, of a fluid pressure operated regulator therein for maintaining constant pressure in the conduit on the outlet side of the regulator, means controlled by fluid pressure for admitting fluid under pressure to operate the regulator, means for causing a drop in pressure at a point in the conduit, and means operated by the variations in this drop in pressure and adapted to impose a gravity load upon the pressure fluid admitting means to increase the pressure in the conduit as the flow past the point of drop increases.

3. The combination with a conduit, of a regulator operated by fluid under pressure and adapted to automatically maintain a constant outlet pressure in the conduit, a master valve controlled by fluid under pressure in the conduit acting in opposition to gravity to admit fluid under pressure to operate the regulator, means for causing drop in pressure at a point in the conduit, and means operated by fluid pressures on each side of the point of drop and adapted to increase the gravity load on the master valve as the flow past the point of drop increases.

4. The combination with a conduit, of a regulating valve therein, means operated by fluid under pressure for shifting the valve to maintain a constant outlet pressure in the conduit, a master valve controlled by the outlet pressure of the conduit operating in opposition to gravity to admit fluid under pressure to the regulating valve operating means to close the valve as the pressure increases and open it as it decreases, means for

causing a drop in pressure at a point in the conduit, and means operated by the fluid pressures on opposite sides of the point of drop and adapted to increase the effect of gravity upon the master valve.

5. The combination with a conduit, of a regulating valve, fluid pressure operating means for shifting the regulating valve, a master valve controlled by fluid pressure in the conduit operated in opposition to a gravity load on the master valve for admitting fluid under pressure to the regulating valve operating means, and means controlled by a differential pressure at a point 10 in the conduit and adapted to increase the gravity load on the master valve as the flow past the point of differential pressure increases.
15. 6. The combination with a conduit, of a

regulating valve, a shiftable member for 20 operating the valve adapted to be moved by fluid under pressure, a master valve controlled by pressure in the conduit acting in opposition to a gravity load and adapted to admit fluid under pressure to the regulating member, means for causing a drop in 25 pressure at a point in the conduit, and means controlled by variations in this drop in pressure for increasing the gravity load on the master valve when the flow past the 30 point of drop in the conduit increases.

In testimony whereof I affix my signature in presence of two witnesses.

ERNEST F. LLOYD.
